UNITED STATES PATENT OFFICE

FREDERICK A. ANTON, OF TOPEKA, KANSAS

ARM FOR LATERAL ARM AWNINGS

Application filed August 18, 1930. Serial No. 476,052.

This invention relates to lateral arm awnings and has for its general object to produce an improved arm construction particularly adapted for wide awnings whereby such awnings when folded, shall occupy a relatively smaller vertical area across the front of a building. In modern store front construction architects are striving more and more to reduce exterior impedimenta, such as awnings, unless they can be folded to a small area and be thus relatively inconspicuous, and one method of accomplishing this result has been to reduce the height or width of the transom bar or awning boxing of windows, and to demand that, when the awning is folded, it shall not occupy a vertical space greater than the width of the transom bar or boxings built to receive the folded awning.

No particular difficulty has been encountered in constructing narrow awnings, such as, for example, a six foot awning which may be readily folded within the modern, narrow transom bar, but with gradually increasing width of sidewalk, it has become more and more desirable that the awning shall increase in width to maintain the architectural harmony of the whole.

In an endeavor to meet the trend of the demand, it has been found that the awning width must, on the whole, be increased and at the same time the construction must be such, that when the awning is folded, its vertical height must not exceed, or materially exceed, the vertical height or width of the smaller or six foot awning.

Originally and before the architectural demand for a narrow transom bar was in vogue, there was no particular difficulty in meeting these demands, as it was merely necessary to increase the width of the material in the arms by using wider, and sometimes thicker, stock. However, when the architects commenced to employ narrow transom bars, difficulty was encountered in supplying the demand for the large sizes.

The prime object of the invention, therefore, is to produce an awning arm which is sufficiently strong to support wide awnings,

but which, when folded, will occupy a vertical space of limited area.

With the general object named in view, and others as will hereinafter appear, reference is to be had to the accompanying drawings, in which:

Figure 1 is a side view of an awning arm embodying the invention.

Figure 2 is a top plan view of the same.

Figure 3 is an enlarged detail to more clearly illustrate a part of the awning arm construction.

Figure 4 is an enlarged view of the opposite side of the upper arm from that shown in Figure 1.

Figure 5 is an enlarged end view of the upper arm to illustrate the inclined relationship between the upper and lower bars of such arm.

In the said drawings, where like reference characters identify corresponding parts in all of the figures, 1 indicates a supporting bracket and 2 the roller on which the awning fabric 3 is wound. The bracket and roller are secured to the transom bar of the window in any suitable manner, not shown. Pivoted to the bracket 1 on a bolt 4, having its upper end inclined outwardly from the vertical, is the upper bracket 5 of an upper awning arm, said bracket being provided with a recess for the reception of an edgewise or substantially perpendicular bar 6 having its lower end received within a recess in a lower bracket 7. The upper and lower brackets 5 and 7 are provided with additional recesses for the reception of the opposite ends of a horizontally arranged bar 8, which is bowed or sprung upwardly by means of a brace 9 embracing the upper and lower bars 6 and 8. Pivoted to the end of the lower bracket member 7 is a second or outer awning arm 10 which is pivotally secured to the cross bar 11 carrying the free end of the awning fabric 3.

It will be noted that the upper arm 6 is inclined downwardly at a considerable angle, this relationship of parts being necessary so that the awning fabric 3 shall not contact with the arms in the folding and unfolding movements of the awning.

In awnings of this character means must

be provided to prevent the awning arms from being locked in their closed or collapsed position, and in order to accomplish this result, reference is here made to Figure 5 where it will be noted that the upper and lower bars 6 and 8 of the upper awning arm, have the coinciding plane of their axes inclined from the vertical, so that the natural tendency of said arms when the force maintaining the roller 2 against movement is released, is to gravitate downwardly and outwardly around its pivot bolt 4 to effect opening or unrolling movement of the awning. The relationship of the parts is essential if it is desired to have an awning which will not lock in closed position and may only be remedied by those awning arms not thus constructed, by providing a stop of some character to prevent the awning arm from being completely folded. This method of construction is objectionable as if the awning arm is not completely folded, it is obvious that it occupies a greater vertical plane when in collapsed position and is also more subject to vibration and injury by the wind.

With an upper awning arm of the character disclosed in this application, particularly when the planes of the upper and lower bars of the upper arm is inclined from the vertical as above described, the load imposed by the awning bar 11 is very great and there is a tendency to twist the upper and lower bars 6 and 8 on an axis substantially half way between the centers of the two bars. With previous constructions, as far as applicant is aware, this difficulty has been, to some extent, obviated by making the upper awning bracket of greater height than the lower awning bracket, so that the upper end of the upper bar was a greater distance from the lower bar than its lower end, the upper bar, because of its better leverage, thus resisting the load imposed on the lower or outer end of the upper arm, but no means was found to overcome the twisting action hereinabove alluded to.

Applicant has found, however, that the load and the twisting strain can be overcome without increasing the height of the upper bracket as compared with the lower bracket and the weight of the upper bar materially reduced, by placing the upper bar with its greatest width extending relatively horizontal and then placing the same under tension by bowing it with the brace connection 9.

With this construction the perpendicular bar 6 takes care of the bending strain or load and the horizontal bar 8 because of the tension placed on it by its bridging relationship, will resist the twisting strain. With this construction, also, when the twisting strain occurs, greater resistance against twisting will be offered because the two bars will not twist in unison or around a center. The perpendicular bar 6 when twisting will tend to force

the horizontal bar 8 to abandon a straight line in one direction and in order to do this will itself tend to bend, but inasmuch as the latter is strong enough to resist bending and the horizontal bar 8 is also strong enough to resist bending, it will be very nearly impossible to force this combination of bars to twist.

From the above description it will be apparent that I have produced an awning embodying the improvement set forth as desirable in the statement of the object of the invention, and which may be readily modified in various details within the spirit and scope of the appended claims.

I claim:

1. The combination in a lateral arm awning, comprising an upper hinge bracket adapted to be secured to a building, an arm secured to said hinge bracket and extending downwardly and outwardly and being laterally inclined from the vertical and consequently under strain tending to rotate same on its longitudinal axis and to simultaneously move its outer end downwardly, a second hinge bracket carried by the outer end of said arm, and a bridge between said hinge members to reinforce said arm against downward and twisting strain.

2. An arm for lateral arm awnings, comprising a bar having its greatest width arranged substantially vertically, a pivot bracket secured to each end of said arm, and a second bar secured to said brackets and bowed away from said first-named bar.

3. An arm for lateral arm awnings comprising a bar having its greatest width arranged substantially vertically, a pivot bracket secured to each end of said arm, a second bar secured to said brackets and bowed away from said first-named bar, and a connection between said first and second bars to maintain said second bar in bowed relationship to the first-named bar.

4. An awning bracket having a pair of aligned bolt-receiving openings and a pair of bar receiving recesses arranged with their corresponding axial planes bearing an inclined relation to the plane of said bolt openings.

5. The combination in a lateral arm awning of an upper hinge member adapted to be secured to a building, an arm secured to said hinge bracket and extending downwardly and outwardly from the building, said arm comprising a lower edgewise bar and a horizontal bar bowed away from said edgewise bar, and a connection between said bars for maintaining the bowed bar in fixed relation.

In testimony whereof I affix my signature.

FREDERICK A. ANTON.
